UNITED STATES PATENT OFFICE.

CHARLES EDWARD LATSHAW, OF LINCOLN, NEBRASKA.

BABY-EXERCISER.

SPECIFICATION forming part of Letters Patent No. 655,631, dated August 7, 1900.

Application filed September 25, 1899. Serial No. 731,690. (No model.)

To all whom it may concern:

Be it known that I, CHARLES EDWARD LATSHAW, residing at Lincoln, in the county of Lancaster and State of Nebraska, have invented certain new and useful Improvements in Baby-Exercisers, of which the following is a specification.

My invention is an improvement in so-called "baby-jumpers" or apparatus for supporting infants elastically, so that they may use their legs freely in springing or jumping, thus combining the benefits of exercise and amusement without requiring close watching or attendance by the mother or nurse.

15 The features of general construction and special novelty are as hereinafter set forth, reference being had to the accompanying drawings, in which—

Figures 1 and 2 are different side views of 20 my improved baby-exerciser, and Fig. 3 is a rear view of the body-girdle or waist-forming part thereof. Figs. 4 and 5 are perspective views illustrating the practical operation and use of the exerciser.

25 A strap *a* serves to suspend the exerciser as a whole from a screw or other fixed device. A spiral spring *b* is pendent from said strap *a* and connected at its lower end with the central coils of a wire spring *c*, which is nearly 30 straight and held normally in horizontal position. The ends of this spring *c* are formed into hooks *c'*, which are inclined downward at an angle of about forty-five degrees, and, being at the top, they allow the obtuse-angle 35 springs *d* to be readily inserted and detached, and, being long, they hold said springs securely, so that they are not displaced by the jumping of an active child. In detachable engagement with such main spring *c* I em-

40 ploy two auxiliary angle-springs *d d*, the same being suspended from the hooks *c'* and arranged parallel to each other and at right angles to the main spring *c*. Said springs *d* have an acute angle, and their arms project 45 an equal distance on opposite sides of the hooks *c'*. They are adapted to rock or oscillate on the latter and may be easily engaged with or detached therefrom, as occasion requires.

50 A suspending girdle or waist *g* is provided for temporary attachment to the body of a

child, and it is suspended from the extremities of the two angle-springs *d* by means of four straps *f*. The latter are provided at each end with snap-hooks *e*, which permit 55 convenient attachment and detachment. The said straps may be attached to the waist *g* by means of eyes *i*. The girdle or waist *g* is formed of cloth—say canton-flannel—and consists of a band for encircling the child's body 60 and a flap which in practice passes between its legs and is drawn up in front and pinned to the overlapped portions of the girdle. The latter is cut out at *h* to accommodate the arms of the child and is provided with one or more 65 plaits at *k*.

Fig. 4 shows the exerciser in use, supporting a child who is in the act of jumping.

Fig. 5 illustrates the angle-springs *d* detached from the main spring *c* and employed 70 as handholds, by which an adult may support a child while exercising or giving him first lessons in walking. It will be seen that in this case, as when the angle-springs are attached to the main spring *c*, they hold the 75 straps *f* widely separated, so that the latter do not chafe or bind the arms and shoulders of the child, but leave them free as possible for any desired movement and at the same time furnish a duly-elastic support or means 80 of suspension.

The snap-hooks *e* enable the straps *f* to be readily detached from the angle-springs as well as the girdle, and all parts of the apparatus are thus adapted to be easily and 85 quickly put together or separated, as occasion requires.

Having thus described my invention, what I claim, and desire to secure by Letters Patent, is—

In a baby-exerciser, the combination, with the main or horizontal spring having dependent hooks which are arranged as specified, of the two obtuse-angle springs *d*, adapted 90 for attachment to and suspension from said hooks, and the girdle and four straps attached thereto and to ends of the angle-springs, as shown and described.

CHARLES EDWARD LATSHAW.
